UNITED STATES PATENT OFFICE

132,518

DESIGN FOR A COCKTAIL TABLE

Anthony O. Mattucci, Oak Park, Ill.

Application January 21, 1942, Serial No. 105,339

Term of patent 3½ years

To all whom it may concern:

Be it known that I, Anthony O. Mattucci, a citizen of the United States, and residing in the village of Oak Park, in the county of Cook and State of Illinois, have invented a new, original, and ornamental Design for a Cocktail Table, of which the following is the specification, reference being had to the accompanying drawings, forming a part thereof.

In the drawings:

Fig. 1 is a perspective view of a cocktail table, showing my new design;

Fig. 2 is a top plan view; and

Fig. 3 is a rear elevational view thereof.

I claim:

The ornamental design for a cocktail table, substantially as shown.

ANTHONY O. MATTUCCI.
